UNITED STATES PATENT OFFICE.

JOHN J. BRERETON, OF TROY, NEW YORK.

CONCRETE RAILROAD-TIE.

991,420.

Specification of Letters Patent. Patented May 2, 1911.

Application filed January 18, 1911. Serial No. 603,362.

To all whom it may concern:

Be it known that I, JOHN J. BRERETON, a citizen of the United States, residing at Troy, in the county of Rensselaer and State 5 of New York, have invented certain new and useful Improvements in Concrete Railroad-Ties, of which the following is a specification.

This invention is primarily designed to 10 construct a durable and simple means whereby the rails may be securely fastened to a concrete tie whereby there will be little or no tendency to break or crumble the concrete as the train passes thereover.

15 The invention resides in the provision of resilient means which the train will cause to yield in passing thereover.

With the above and other objects in view, 20 this invention consists in the construction, combination and arrangement of parts, all as hereinafter more fully described.

Figure 1 is a plan view illustrating the rails secured to the tie; Fig. 2 is a side elevation of the railroad tie, one portion thereof 25 of being in section to further disclose the present invention; Fig. 3 is a transverse section of the tie; Figs. 4, 5 and 6 are details used in the construction of the present invention.

30 Throughout the following detail description and on the several figures of the drawings, similar parts are referred to by like reference characters.

In constructing the concrete railroad tie 35 in accordance with the present invention, the tie 1 is provided with a plurality of tubular members 2 mounted therein. Embedded in the under surface of the tie is a pair of plates 4, one being located adjacent to each 40 terminal of the tie. The said plates 4 are provided with apertures through which bolts 3 are inserted, said bolts extending through the tubular members 2 and projecting above the upper surface of the tie 1. 45 The tubular members 2 extend a little above the upper surface of the tie and are adapted to pass through openings provided in the resilient or yielding member 5 which lies flat upon said upper surface. A bearing plate 50 6 is placed in superposed relation to the

yielding member 5, said bearing plate being provided with openings through which the bolts 3 are adapted to pass. The bolts 3 are provided with threaded terminals to which nuts are applied to secure the clamping member 7 upon the bearing plate 6, thereby retaining the rail 8 in its operative position. 55

The bearing plate 6 is held in spaced relation to the resilient member 5 by a plurality of spring tongues or members 10 pressed upwardly from the plate 5, as illustrated in Fig. 5. The bearing plate 6 is retained in spaced relation to the resilient plate 5 by a second means, viz., sockets 9 which are 60 flared to receive the beveled terminals 12 of the tubular members 2. The upper terminals of the tubular members are slotted, as illustrated in Fig. 6, to provide spring sections 11. 65

70 It will be understood that, as the train or car passes over the rail, there will be a yielding of the spring tongues 10, and also a contraction of the spring sections 11, as will obviously be seen. From the above construction, it will be observed that there will be a minimum tendency to injure the concrete tie by passing trains, and thereby prolong life. 75

The reinforcing elements of the tie may be provided in the usual manner having the 80 longitudinal reinforcing rods 13 and the vertical rods 14 which retain said longitudinal rods in spaced relation when forming the tie.

Having thus fully described my invention, 85 what is claimed as new is:—

1. The combination with a rail, of a tie, a plurality of tubular members carried by said tie, a yielding member provided with integral spring projections, a bearing member provided with sockets adapted to receive said tubular members, said bearing member being retained in spaced relation to said yielding members by said spring projections, and clamping means adapted to clamp said rails 90 on said bearing members, as set forth. 95

2. The combination with a rail, of a tie, a plurality of tubular members mounted in said tie, the upper terminals of said tubular members being slotted, a yielding member 100

carried by said tie and provided with integral spring projections, a bearing member retained in spaced relation with said yielding member by said projections, a plurality 5 of sockets carried by said bearing member and adapted to receive the slotted terminals of said tubular members, clamping members adapted to retain the rail in operative posi-

tion, and means for retaining said clamping members to said tie, as herein set forth.

10

In testimony whereof I affix my signature in presence of two witnesses.

JOHN J. BRERETON.
